UNITED STATES PATENT OFFICE.

MAX ABRAHAMS, OF NEW YORK, N. Y.

DESIGN FOR AN ACOUSTIC HORN.

Application filed August 13, 1926. Serial No. 18,735. Term of patent 14 years.

To all whom it may concern:

Be it known that I, MAX ABRAHAMS, a citizen of the United States of America, residing at New York city, in the county and State of New York, have invented a new, original, and ornamental Design for Acoustic Horns, of which the following is a specification, reference being had to the accompanying drawing, forming part thereof.

The figure is a perspective view of the acoustic horn showing my new design.

I claim:

The ornamental design for an acoustic horn as shown.

MAX ABRAHAMS.
